(57) CLAIM

The ornamental design for thermal solar cell design, as shown and described.

DESCRIPTION

FIG. 1 is a perspective view of a thermal solar cell design showing my new design;

FIG. 2 is a top plan view thereof;

FIG. 3 is a bottom plan view thereof;

FIG. 4 is a front view thereof;

FIG. 5 is a back view thereof;

FIG. 6 is a first side view thereof;

FIG. 7 is a second side view thereof;

FIG. 8 is a perspective view of a second embodiment of a thermal solar cell design;

FIG. 9 is a top plan view thereof;

FIG. 10 is a bottom plan view thereof;

FIG. 11 is a front view thereof;

FIG. 12 is a back view thereof;

FIG. 13 is a first side view thereof; and,

FIG. 14 is a second side view thereof.

The broken lines shown represent unclaimed subject matter and form no part of the claimed design.
